Attorney, Agent, or Firm—Rhodes, Coats & Bennett

[57] CLAIM

The ornamental design for a jar evacuating and sealing apparatus, as shown.

DESCRIPTION

FIG. 1 is a perspective view of a jar evacuating and sealing apparatus showing my new design;

FIG. 2 is a top plan view;

FIG. 3 is a side elevational view, the opposite side being the same in appearance; and

FIG. 4 is a bottom plan view thereof.
